UNITED STATES PATENT OFFICE.

BERNARD T. LEVEQUE, OF WENHAM, MASSACHUSETTS, ASSIGNOR TO UNITED SHOE MACHINERY CORPORATION, OF PATERSON, NEW JERSEY, A CORPORATION OF NEW JERSEY.

CAST-OFF MECHANISM FOR SEWING MACHINES.

Original application filed February 2, 1924, Serial No. 690,265. Divided and this application filed February 15, 1927. Serial No. 168,258.

The present invention relates to cast-offs for hook needle sewing machines and is herein disclosed as embodied in a chain stitch shoe sewing machine of the so-called McKay type, the stitch forming devices of which comprise a straight hook needle and the work support of which consists of a rotatable horn arranged to extend within the shoe and provided at its tip with a needle threading 5 vice or whirl for laying the thread in the hook of the needle.

The primary object of the invention is to produce a new and improved cast-off mechanism particularly adapted for use in machines of this description which is simple and durable in construction and will operate accurately and without excessive wear at high speeds.

A further object of the invention is to provide a new and improved cast-off mechanism which will operate to leave the needle hook uncovered when the needle is stopped at the limit of its loop drawing stroke.

With these objects in view the several features of the invention consist in the devices, combinations and arrangement of parts hereinafter described and claimed, certain of which, while particularly adapted for use in sole sewing machines of the McKay type, are also capable of use in other types of sewing machines.

The several features of the invention and the advantages obtained thereby will be readily understood by those skilled in the art from the following description taken in connection with the accompanying drawings which illustrate the invention as embodied in a chain stitch McKay sewing machine.

The drawing is a view in front elevation of the head of a chain stitch McKay sewing machine embodying one form of the present invention only so much of the machine being illustrated as is necessary to show the connection of the present invention therewith.

For a full description of the machine, reference may be had to the inventor's pending application Serial No. 690,265, of which the present application is a division.

The cast-off mechanism embodying specifically the subject matter of the present invention comprises a supporting collar to which the cast-off is secured loosely sleeved on the needle bar to slide between set stops on

the bar, and two oppositely arranged spring pressed levers provided with cam surfaces 55 adapted to engage a roll on the collar and so control the movement of the cast-off with relation to the needle.

The yielding cam levers take the place of the friction devices usually employed to secure a delayed motion of the cast-off with relation to the needle and also act to impart an additional movement to the cast-off in the direction of movement of the needle bar at the end of the stroke in each direction to uncover 60 the needle bar at the top of the stroke and to project the cast-off yieldingly into contact with the work on the down stroke of the needle.

Referring specifically to the drawings, the 70 needle is indicated at 4, the presser foot at 6, the feed point at 8, a horn of usual construction at 10, and the cast-off at 12.

The straight hook needle 4 is secured to the lower end of the needle bar 14, which is slidably mounted in bearings in the machine frame and is reciprocated from a crank pin 16 on the forward end of the sewing shaft 18 through connections which are adapted to give a variable throw to the needle bar as the 80 work varies in thickness and to permit the needle bar to be disconnected from the sewing shaft at the top of its stroke at the end of the sewing operation. To reciprocate the needle bar a block 20 is secured to the bar 85 and is connected by a link 22 to a lever 24 pivoted at 26 to a lever 28, which lever is secured at its right-hand end to a pivot shaft 30. The right-hand end of the lever 24, as viewed from the front end of the machine, is 90 provided with a curved slot 32, which is engaged by a block 34 pivotally mounted on the upper end of an arm 36, which is automatically adjusted to vary the throw of the lever 24, and the needle bar 14, in accordance with 95 the thickness of the work. The lever 28 is actuated to drive the needle bar by means of a lever 38 mounted parallel to the lever 28 and secured at its right-hand end to the sleeve 40 surrounding the pivot shaft 30 of the lever 100 28. A cam slot 44 is formed in the lever 38, which cam slot is engaged by the crank pin 16 so that during the rotation of the cam shaft the lever 38 is continuously oscillated. To cause the lever 28 to oscillate with the 105 lever 38 a latch 46 is mounted upon the left-

hand end of the lever 28 and is arranged to engage a pin 48 on the lever 38. During the sewing operation the latch is held in engagement with the pin by means of a spring surrounding the pivot of the latch.

As more fully pointed out in the inventor's pending application above referred to, the machine is provided with connections from the starting and stopping treadle for actuating the latch 46 to disconnect the needle bar from the sewing cam shaft as the needle bar reaches the top of its stroke. These connections include a vertically arranged lever arm 50 provided at its upper end with a cam groove 52 which is adapted to receive a roll 54 mounted on the needle actuating lever 28. During the operation of the machine the lever 50 is swung yieldingly to the right so that the roll 54 rides on the left side of the cam groove. However, when the treadle is lifted to stop the machine, the lever 50 will be swung yieldingly to the left so that the roll 54 riding up the right side of the cam groove will enter the notch 58 locking the needle lever in raised position. At the same instant, the latch 46 will be disconnected from the lever 38 which will continue to oscillate with each rotation of the sewing cam shaft.

The mechanism for actuating the cast-off herein disclosed, is simple and durable in construction, and is adapted to operate accurately and without excessive wear at the unusually high speed at which the chain stitch McKay sewing machine embodying the present invention is intended to operate. Furthermore, in order to permit the operator more readily to disengage the thread from the barb of the needle after the machine has come to rest without cutting the thread, the cast-off mechanism is actuated in such a manner as to leave the needle hook uncovered at the limit of the loop drawing stroke so that when the sewing mechanism is stopped, the needle hook will be uncovered. This is of advantage, for instance, when an imperfection occurs in the seam for the operator can then, merely by pulling the shoe off and away from the horn, rip out the stitches which have been sewed as far back along the seam as he desires.

The cast-off 12 is mounted to slide in a groove in the needle bar and is secured at its upper end by means of a bolt 62, through which the cast-off passes, to a collar 60 loosely sleeved to the needle bar 14. A slot 64 is cut in the needle bar to receive the head of the bolt which is provided at its outer end with a nut 66 to actuate the bolt so as to clamp the cast-off firmly against the inner face of the collar 60. This collar is mounted to slide on the needle bar between the block 20 and a collar 68 secured to the needle bar. Upon the collar 60 is mounted a roll 70 which, as the needle bar is moved up and down, passes between the upper ends of levers 72 and 74 pivotally mounted on the machine frame and

connected at the lower ends by intermeshing teeth, whereby their upper ends are caused to move toward and from each other in unison. The upper ends of the levers are forced together by a spring 76 connecting the levers. The levers contact at a point and the surfaces of the levers diverge both above and below this point.

The operation of the cast-off mechanism is as follows: On the down stroke of the needle the collar 20 on the needle bar will come into contact with the collar 60 supporting the cast-off which is in raised position and move it downwardly so that the roll 70 is forced between the upper ends of the levers 72. As the needle bar reaches the limit of its down stroke, the roll will have moved past the point of contact of the levers 72 and is given an additional impulse downward into yielding engagement with the work by the contracting action of the levers under the influence of the spring 76. During the retracting or loop drawing stroke of the needle, the cast-off remains in contact with the work until the needle hook is covered, when the collar 60 will be engaged by the collar 68 secured to the needle bar moving the cast-off upwardly with the needle and causing the roll 70 again to pass between the levers 72 which act as the needle reaches the limit of its loop drawing stroke to give the cast-off an additional impulse upwardly to uncover the needle hook.

The nature and scope of the invention having been indicated and a form of the invention having been specifically described, what is claimed is:

1. A sewing machine having, in combination, stitch forming devices including a straight hook needle, a cast-off movable with the needle and having a limited independent movement, a pin connected to the cast-off, and a yielding member engaged by the pin during the needle movement provided with a cam surface for moving the cast-off to uncover the needle hook as the needle reaches the limit of its loop drawing stroke.

2. A sewing machine having, in combination, stitch forming devices including a straight hook needle, a cast-off movable with the needle and having a limited independent movement, a pin connected to the cast-off, and a yielding member engaged by the pin during the needle movement provided with cam surfaces for moving the cast-off with relation to the needle in the direction of needle movement during the movement of the needle in each direction.

3. A sewing machine having, in combination, stitch forming devices including a straight hook needle, a cast-off movable with the needle and having a limited independent movement, a pin connected to the cast-off, and yielding members, between which the pin passes during the needle movement, connected to move in unison towards and from each

- other and provided with cam surfaces for moving the cast-off to uncover the needle hook as the needle reaches the limit of its loop drawing stroke.
5. A sewing machine having, in combination, stitch forming devices including a straight hook needle, a needle bar provided with a groove, a sleeve loosely mounted to move on the needle bar with and independently of the needle, and a cast-off mounted to slide in said groove secured to the sleeve.
5. A sewing machine having, in combination, stitch forming devices including a straight hook needle, a cast-off mounted to move with and independently of the needle, and means for imparting to the cast-off an additional impulse in the direction of the needle stroke to uncover the needle bar at the end of the loop drawing stroke and to bring the cast-off yieldingly into contact with the work on the down stroke of the needle.
6. A sewing machine having, in combination, stitch forming devices including a straight hook needle, a cast-off mounted to move with and independently of the needle, means for causing the cast-off to move with the needle and means for imparting to the cast-off an additional impulse on the down stroke of the needle to bring the cast-off yieldingly into contact with the work.
7. A sewing machine having, in combination, stitch forming devices including a straight hook needle, a needle bar, a sleeve loosely mounted to move on the needle bar with and independently of the needle, and a cast-off movable with the needle and having a limited independent movement, a pin connected to the cast-off, and a yielding member engaged by the pin during the needle movement provided with a cam surface for moving the cast-off yieldingly towards the work as the needle reaches the limit of its down stroke.
8. A sewing machine having, in combination, stitch forming devices including a straight hook needle, a cast-off movable with the needle and having a limited independent movement, a pin connected to the cast-off, and a yielding member engaged by the pin during the needle movement provided with a cam surface for moving the cast-off yieldingly towards the work as the needle reaches the limit of its down stroke.
9. A sewing machine having, in combination, stitch forming devices including a straight hook needle, a needle bar, a cast-off adapted to slide in a groove in the needle bar, a sleeve loosely mounted to move on the needle bar, and means for clamping the cast-off to the inner surface of the sleeve.
10. A sewing machine having, in combination, stitch forming devices including a straight hook needle, a needle bar, a cast-off adapted to slide in a groove in the needle bar, a sleeve loosely mounted to slide on the needle bar, a bolt through which the cast-off passes extending outwardly through the sleeve, and a nut for tightening the bolt to clamp the cast-off to the inside of the sleeve.

In testimony whereof I have signed my name to this application,

BERNARD T. LEVEQUE.
